United States Patent Office

Des. 184,525
Patented Mar. 3, 1959

184,525

TRAY FOR MEATS AND THE LIKE

Robert Lurie, Jacksonville, Fla., assignor to Lurie
Industries, Inc., Jacksonville, Fla.

Application August 4, 1958, Serial No. 52,023

Term of patent 14 years

(Cl. D44—10)

Fig. 1 is a top plan view of a tray for meats and the like showing my new design;

Fig. 2 is a cross-sectional view on line 2—2 of Fig. 1;

Fig. 3 is a cross-sectional view on line 3—3 of Fig. 1; and

Fig. 4 is a side elevational view.

I claim:

The ornamental design for a tray for meats and the like, as shown.
